UNITED STATES PATENT OFFICE.

EMIL J. GUNSELL, OF ST. PAUL, MINNESOTA.

PEN-EXTRACTOR.

1,164,506.

Specification of Letters Patent. Patented Dec. 14, 1915.

Application filed September 8, 1914. Serial No. 860,761.

To all whom it may concern:

Be it known that I, EMIL J. GUNSELL, a citizen of the United States, residing at St. Paul, in the county of Ramsey and State of Minnesota, have invented certain new and useful Improvements in Pen-Extractors; and I do hereby declare the following to be a full, clear, and exact description of the invention, such as will enable others skilled in the art to which it appertains to make and use the same.

This invention relates to improvements in pen extractors such as may be used in an ordinary writing pen, and an object of the invention is to provide an extractor which may be used as a guard, ink eraser, pen support and pencil sharpener.

A further object of the invention is to provide an extractor easily gripped by the fingers and so connected to the pen point that the latter may be removed without the necessity of touching the same.

With these and other objects in view the invention consists of the arrangement, construction and combination of parts as will be more particularly described and claimed hereinafter.

In the accompanying drawings: Figure 1 is a bottom plan view of an ordinary pen holder showing the pen point and extractor in dotted lines; Fig. 2 is a vertical section taken on line 2—2 of Fig. 1; Fig. 3 shows a portion of a pen point with the extractor forming the subject matter of the present invention attached thereto; Fig. 4 shows the pen extractor operating as a support for the pen.

Similar reference characters indicate like parts throughout the several views.

In the present specification a description will be given of one of several forms of ordinary pen holders which will be found upon the market, after which the application of my pen extractor to the ordinary form of penholder will be described.

Fig. 1 shows the ordinary pen holder having the staff 1 provided with the usual ferrule 2 which forms a guard for the bore 3 formed in the end of the staff 1 and proportioned to receive the split sleeve 4 divided at the bottom as at 5 so that the same may be compressed when it is desired to insert the sleeve within the bore 3. Prongs 6 are formed rigid with the sleeve 4 as will be seen in Fig. 1 and extend beyond the tip of the sleeve. There is a space

defined between the prongs as seen at 8 which makes it possible to use the form of pen extractor described hereinafter. The prongs 6 are resilient and are designed to press the shank of a pen point against the sleeve 4. The outer end of the projecting portion 7 of the sleeve may be provided with a notch 9 in alinement with the space 8 between the prongs to accommodate the pen extractor, as will be described hereinafter.

While I have described a form of pen wherein the sleeve is removed from the end of the staff, I do not wish to be limited to this construction inasmuch as the vital parts of the ordinary pen so far as my present invention is concerned are the prongs 6 with the space therebetween and the sleeve 4.

Referring now particularly to Figs. 2 and 3, there will be described the pen extractor which forms the subject matter of the present invention. The extractor as seen more clearly in Fig. 3 comprises a resilient strip 80 having a substantially straight arm 10, the end of which is provided with a pointed offset 11 which when the parts are assembled will extend upwardly through a slot 12 formed in the top of the pen point shank. 85 The offset 11 is preferably just long enough to engage the sides of the pen point shank defining the slot without extending appreciably beyond the slot, although, of course, this particular feature is of minor importance.

The extractor is rounded as at 13 and may be provided with the offset 14 to increase the resilience thereof. Extending from the offset 14 there is an arm 15 terminating in a finger 16 extending in such a direction as to be substantially at right angles to the pen holder when the extractor is in position as seen in Figs. 2 and 4. The pen and extractor before insertion in the holder have about the position shown in Fig. 3, but when the extractor is inserted within the sleeve as seen in Fig. 2 the lower arm 15 is pressed upwardly so that the same is substantially parallel to the upper arm 10, these arms being forced against the adjacent part by reason of the resiliency of the extractor.

By referring to Fig. 1, it will be seen that the forward end of arm 10 which carries the offset 11 lies within the space 8 between the prongs 6 so that the application of my extractor to the ordinary pen holder does not in any way interfere.

with the action of the prongs nor does it require any change in the construction of the ordinary pen holder. In certain constructions of the extractor the offset 11 may be engaged in and be limited in rearward movement by the notch 9 in the portion 7 of the sleeve to prevent rotation of the extractor. If the notch be not provided, this movement will be prevented by the engagement of the offset 11 with the prongs of the pen holder.

The pen point is of ordinary construction with the exception that the shank thereof is provided at a suitable point with the slot 12. This slot may be placed at any suitable point depending upon the length of pen point which it is desired to have extend beyond the sleeve 4. The ordinary pen point is parti-cylindrical and a convenient way of providing the slot 12 is to remove a portion of the shank adjacent the top of the pen by filing, grinding or other means. Otherwise the pen point is identical with the usual pen point construction. By referring to Fig. 4, it will be seen that when the pen point is in its inmost position the finger 16 engages the bottom of the sleeve 4.

When it is desired to insert the pen point within the holder the extractor will first be inserted within the sleeve 4 and pushed as far backwardly as possible after which the shank of the pen point will be inserted between the top of the sleeve and the comparatively straight arm 10 of the extractor, the offset 11 engaging the end of the shank and serving to guide the same. The pen point is then pushed into the holder until the offset 11 springs into the slot 12. Inasmuch as the arms 10 and 15 of the extractor are substantially parallel and serve to engage the pen point and bottom of the sleeve respectively, there is little if any tendency for the extractor to be pushed outwardly by the resilience of the curved portion 13 and the offset 14. Aside from giving additional resilience to the extractor the offset 14 also reduces the end of the extractor so that it is a simple matter to insert the same within the sleeve. If it is desired to remove the pen point while the same is wet, this may be accomplished by catching the finger 16 between the thumb and forefinger slipping the same outwardly from the sleeve. The length of the arm 10 is considerably greater than the distance between the slot 12 and the butt end of the pen point shank so that the extractor need not be taken entirely from the sleeve in order to remove the pen point.

It will be apparent that the removal of the point does not require that the same be touched.

For the convenience of the person using the pen, the lower edge 17 of the finger 16 may be sharpened and made substantially

straight. With the lower edge straight, the finger will serve as a support for the pen when it is desired to lay the same down as in Fig. 4. Also, when the edge is sharpened, the same may be used as an erasing knife for ink lines, etc., and it is also apparent that the sharpened edge may be used for sharpening pencils, the resilience of the extractor being sufficient to prevent the slipping of the extractor and pen point out of the sleeve. When using the pen, it will be apparent that each time the user reaches for ink the finger 16 will engage the rim of the ink well and the extractor and pen point will be forced backwardly into the sleeve as far as possible by the engagement of the extractor with the rim of the well. Also, should it be desired to remove the pen without grasping the finger 16 between the thumb and forefinger the sharpened edge 17 may be held against a blotter or other suitable means and the pen holder drawn rearwardly at which time the extractor and pen holder will separate and the pen point will be ejected.

What I claim is:

1. A pen holder having a sleeve and spaced resilient prongs located within the sleeve, a resilient extractor located within the sleeve, and an outwardly extending finger rigid with the extractor and having the lower edge thereof sharpened to engage an obstruction and be held thereby to draw the extractor out of the sleeve when the pen holder is drawn rearwardly.

2. A pen holder comprising a staff made tubular at its lower end, a split sleeve inserted in its bore with the split at the lower side of the staff and the solid side of the sleeve projecting beyond said staff and notched in its outer extremity, spaced resilient prongs secured within the upper side of the sleeve with their space opposite said notch and a resilient extractor located within the sleeve and having an upstanding offset slidably mounted within said space and adapted to engage the notch in the sleeve.

3. A pen holder comprising a staff, a sleeve carried by the staff and projecting beyond its lower end and having a notch in the extremity of its upper side, spaced resilient prongs secured to the sleeve and a resilient extractor comprising upper and lower arms connected by a bend, the arms standing within said sleeve and the upper arm having an offset adapted to project through said notch and the lower arm having a finger projecting beyond the sleeve.

In testimony whereof I affix my signature in presence of two witnesses.

EMIL J. GUNSELL.
